(57) **CLAIM**

The ornamental design for, A front bumper for an automobile,
as shown and described.

DESCRIPTION

FIG. 1 is a perspective view of A front bumper for an automobile, showing our new design;

FIG. 2 is a front elevation view thereof;

FIG. 3 is a top plan view thereof;

FIG. 4 is a right side elevation view thereof; and,

FIG. 5 is a left side elevation view thereof.

The broken lines are for illustrative purposes only and form
no part of the claimed design.
